UNITED STATES PATENT OFFICE

AUGUST W. L. HARTBAUER, OF CHICAGO, ILLINOIS

CAR CONSTRUCTION

Application filed November 19, 1928. Serial No. 320,399.

This invention relates to railway train refrigerator and box cars, and has for its object to provide a construction wherein the side wall is ventilated to reduce the amount of moisture permitted to come in contact with the insulation of a refrigerator car wall or the side wall of a box car, and furthermore to provide a metallic sheathing on the outside of the wall of the car and spaced apart therefrom to provide an air chamber, which chamber is provided with openings near the top and bottom thereof, respectively, so as to permit circulation of air between the wall of the car and the sheathing which would prevent hot air from being retained against the car wall and so attach the metallic sheathing to the frame members of the car that it can be readily removed (and replaced) to facilitate the removing, replacing and repairing of the insulation of the car wall or the car wall itself.

Another object is to attach such a removable sheathing to the car at its upper margin (or lower margin if desired) so as to permit relative vertical movement therebetween and so as to prevent any substantial horizontal movement between these elements whereby the weaving and torsional movements of the car in service do not transmit buckling stresses upon the sheathing thereby allowing thinner material to be used for the sheathing plates.

Another object of the invention is to so attach the removable sheathing to the upper plate member of the car so that the plate may act as a hood or shield for the ventilating means for the sheathing.

Another object of the invention is to so attach the removable metallic sheathing to the sill member of the car that the sheathing acts as a hood or shield for the ventilating means adjacent the sill of the car.

Another object of the invention is to form the side or end walls of a car with a retaining wall and a readily removable metallic sheathing spaced apart from each other to form an

air chamber therebetween and to provide ventilating means for the air chamber adjacent the upper and lower frame members respectively of the car and to so arrange the attachments of the sheathing to the upper and lower frame members respectively that the ventilating apertures are shielded or protected from the direct entrance of rain, snow or other forms of moisture therethrough.

In the drawings:

Fig. 1 shows a typical section through the side wall of a refrigerator car formed with my invention.

Fig. 2 shows a modified form of Fig. 1.

Fig. 3 shows a horizontal cross section through one of the vertical frame members of the car.

Fig. 4 is a modified form of Fig. 3.

Fig. 5 shows a typical section through a side wall of a box car formed with my invention.

Fig. 6 shows a side elevation of a part of Fig. 5.

Fig. 7 shows a horizontal section through the side wall shown in Fig. 6.

In the form illustrated in Figs. 1 to 4 inclusive the insulating wall of the car comprises several $1\frac{1}{2}$ " layers of insulating material 2 and inside wooden lining 3, which elements extend from the lower sub-side sill 4 to the upper sub-side plate 5. Nailing strips 6 and 7 hold the upper and lower part of the outer insulating layer 8 in place. The usual wooden flooring 9 and wooden ceiling 10 are shown. Numeral 11 is part of the roof insulation and 12 is part of the floor insulation. The rolled steel upper side plate 13 and the rolled steel lower side sill 14 form the oppositely disposed longitudinal side frame members of the car which are connected by vertical and diagonal steel members or posts and braces to form a truss. These vertical and diagonal members are not shown except as 15 and 16 in Figs. 3 and 4.

It is customary to nail vertical sheathing

boards over the outside of the insulating wall but the weaving and other movements of the car in motion loosen the nails, crack the boards and separate them so that they leak and permit moisture to come in contact with the insulating material, which material acts like a sponge and readily absorbs it and transfers the moisture to the adjacent insulating layers. The increased weight of the insulation caused by the moisture content causes it to break away from its moorings and it is jarred to the lower part of the car, thus, of course, at least partially depriving the car of its insulation. Even though the insulating material is not displaced its insulating capacity is materially reduced by becoming moist.

My invention is an improvement on such construction as I eliminate the wooden sheathing and substitute therefor a metallic sheathing 20 which cannot be cracked or split or otherwise damaged so as to permit the water to come in contact with the insulation. Furthermore, I provide an air chamber 21 between the insulation 8 and metallic sheathing 20 and also provide means of ventilating this air chamber, thus preventing any condensation on the inside of the metallic plate from wetting the insulation.

It is understood, of course, in my invention that moist air (and perhaps driven snow) would and will come in contact with the insulating material and therefore it will become necessary to remove and replace the insulation, therefore, at spaced intervals, I provide angle clips (22) which are rigidly secured to the side plate of the car as at (23) but which are detachably secured by bolts 24 to the metallic sheathing 20. At the lower part of the end wall, at spaced intervals, I provide clips 25 which are rigidly secured to the side sill as at (26) but which are bolted as at (27) through the medium of a continuous connecting angle 28 to the metallic sheathing, 20.

45 The side plate is provided with a depending flange 32 which is spaced away from the metallic sheathing 20 and which overlaps and overhangs the metallic sheathing and the ventilating apertures 30 between adjacent clips 22. (Of course, the apertures may actually be in the side sheathing but this is immaterial as far as this invention is concerned.) The sheathing 20 overhangs the side sills and the ventilating apertures 31 adjacent thereto to prevent rain or moisture from beating directly into the air chamber.

Fig. 2 shows a modified construction wherein the sheathing 20 is provided with integral rigidifying corrugations or embossments 33 which preferably terminate adjacent the posts 16, as shown in Fig. 4. A stiffening flange 34 is provided adjacent the top of the plate 20 and ventilation is provided between the sheathing plate 20 and the depending

flange 32 of the side plate without perforating any of the members.

Fig. 4 shows a readily detachable means of securing the plates 20 to the vertical post 16 wherein a stud rivet 36 secures a continuous strip 37 to the post which frictionally secures the vertical edges of the adjacent plates in place.

Figs. 5 and 6 show a modified form of the invention applied to a box car wherein the retaining wall 40 comprises a plurality of preferably horizontal boards spanning the distance between the upper frame member or side plate 41 and the lower frame member or side sill 42. The floor 43 rests upon the side sill 42. The frame members, such as corner post, door post, intermediate vertical post and diagonal braces, overlap and are secured to the sill and plate. The removable sheathing 45 is spaced apart from the retaining wall 40 preferably an amount equal to the width of the posts. Nailing strips 46 for the retaining wall may be bolted to these posts.

The lower margin of the sheathing is attached by a connecting angle 47 to the spaced apart clips 48. The upper margin of the sheathing is formed with a flange 49 to form a horizontal portion which is provided with an aperture 50. The angular member 51 is secured to the side plate and is provided with a depending piece or tongue 52 which protrudes through and loosely engages the aperture 50. The tongue and aperture may be round but are preferably elongated, as shown in Fig. 6, to minimize the friction and wear between these parts. The aperture is preferably burred (53) to increase the bearing area. This construction permits the sheathing to move up and down relative to the side plate to accommodate the lateral and torsional movements of the car in service, and at the same time, retains the sheathing in a substantially vertical position by preventing any substantial horizontal movement between the sheathing and the side plate. The lower margin of the sheathing is preferably rigidly and removably attached to the side sill. If preferred the loose connection may be positioned at the bottom of the sheathing and the rigid connection at the top of the sheathing.

The side plate is preferably provided with a flange 55 which overhangs and overlaps the ventilating apertures.

Fig. 7 shows how the retaining wall is attached to the door post 57 by the connecting angle 58 and continuous strip 59. This figure also shows the attachment to the corner post 60 by the connecting member 61 and continuous strip 62. A nailing piece 63 may be bolted to the corner post 61.

The accompanying drawings illustrate the preferred form of the invention, though it is to be understood that the invention is not limited to the exact details of construction shown.

and described, as it is obvious that various modifications thereof within the scope of the claims will occur to persons skilled in the art.

5 This is a continuation in part of my application Serial No. 314,213, filed October 22, 1928.

I claim:

1. In a railway car, the combination of oppositely disposed frame members, an insulating wall positioned substantially between said frame members, a metallic sheathing removably secured to said frame members and spaced from said wall to provide an air chamber, and means to ventilate said chamber.

10 2. In a railway car, the combination of oppositely disposed frame members, an insulating wall positioned substantially between said frame members, a metallic sheathing, connecting members attached to said sheathing and removably secured to said frame members, and an air chamber between said sheathing and said wall, said connecting members being perforated to provide means 20 to ventilate said chamber.

3. In a railway car, the combination of a side plate, an insulating wall, a metallic sheathing removably secured to the side plate and provided with ventilating apertures adjacent the side plate, and an air chamber between the wall and the sheathing, said side plate having a depending flange spaced from said sheathing and overhanging said sheathing and said apertures.

35 4. In a railway car, the combination of a side plate member, a side sill member, an insulating wall, a metallic sheathing removably secured to said members and provided with ventilating apertures adjacent said members respectively, and an air chamber between the wall and the sheathing, said side plate having a depending flange spaced from said sheathing and overhanging said sheathing and the apertures adjacent the side plate, said sheathing overhanging the side sill and the apertures adjacent the side sill.

5. In a railway car, the combination of a side plate having an upstanding flange to which a roof is secured, a horizontal web to which a metallic wall is secured, said wall being provided with apertures adjacent said web, and a depending flange spaced apart from said wall and overlapping said apertures.

55 6. In a railway car, the combination of oppositely disposed frame members, a retaining wall positioned between said frame members, a metallic sheathing spaced apart from said retaining wall to provide an air chamber, and means to ventilate said chamber adjacent each of said frame members, said metallic sheathing being rigidly and removably attached to one of said frame members and loosely and removably attached to the other of said frame members.

7. In a railway car, the combination of a frame member, metallic sheathing, and means to permit relative vertical movement between the frame member and the sheathing though preventing any substantial horizontal movement between these elements, said sheathing spaced apart from said frame member and arranged to permit ventilation therebetween.

75 8. In a railway car, the combination of a frame member, metallic sheathing, a horizontal portion on said sheathing provided with an aperture, and a depending piece attached to said frame member protruding through and loosely engaging said aperture so as to provide means to permit relative vertical movement between the frame member and the sheathing though preventing any substantial horizontal movement between these elements, said sheathing spaced apart from said frame member and arranged to 80 permit ventilation therebetween.

90 9. In a railway car, the combination of a frame member having a depending flange, metallic sheathing positioned behind said flange and under said frame member, a horizontal portion on said sheathing provided with an aperture, and a depending piece attached to said frame member protruding through and loosely engaging said aperture so as to provide means to permit relative vertical movement between the frame member and the sheathing though preventing any substantial horizontal movement between these elements, said sheathing spaced apart from said frame member and arranged to 95 permit ventilation therebetween.

100 10. In a railway refrigerator car having an insulated wall, a metallic sheathing secured to said wall and spaced apart therefrom to provide an air chamber between the wall and the sheathing, said air chamber provided with ventilating apertures.

105 11. In a railway car, the combination of a truss comprising longitudinal frame members connected by substantially vertical posts, an insulating wall secured to said truss, and a sheathing secured to said posts in spaced relation to said wall to provide an air chamber therebetween, said air chamber provided with ventilating apertures.

110 12. In a railway car, the combination of a truss comprising longitudinal frame members connected by substantially vertical posts, an insulating wall secured to said truss, and a sheathing secured to said posts and frame members in spaced relation to said wall to provide an air chamber therebetween, said air chamber provided with ventilating apertures.

125 13. In a railway car, the combination of a truss comprising longitudinal frame members connected by substantially vertical posts, an insulating wall secured to said truss, and a metallic sheathing secured to said truss in spaced relation to said wall to provide an air 130

chamber therebetween, said air chamber provided with ventilating apertures, said sheathing formed with rigidifying corrugations.

14. In a railway car, the combination of a truss comprising longitudinal frame members connected by substantially vertical posts, an insulating wall secured to said truss, and a metallic sheathing secured to said posts in spaced relation to said wall to provide an air chamber therebetween, said air chamber provided with ventilating apertures, said sheathing formed with rigidifying corrugations which terminate adjacent said posts.
